THEODORE KOZLOSKY, OF TOLEDO, OHIO, ASSIGNOR OF ONE-THIRD TO ANTHONY OSTACHOWICZ AND STANLEY BABKA, BOTH OF TOLEDO, OHIO.

MILK-BOTTLE CAP.

1,413,592.

Specification of Letters Patent. Patented Apr. 25, 1922.

Application filed March 18, 1921. Serial No. 453,505.

To all whom it may concern:

Be it known that I, THEODORE KOZLOSKY, a citizen of Poland, residing at Toledo, in the county of Lucas and State of Ohio, have invented certain new and useful Improvements in Milk-Bottle Caps, of which the following is a specification.

The main object of this invention is to provide a milk bottle stopper having means 10 for its rapid release and means for sealing the same tightly upon the bottle so as to prevent leakage or spilling of the contents.

The above and other objects will become apparent in the description below, in which 15 characters of reference refer to like named parts in the drawings.

Referring briefly to the drawings:

Figure 1 is a side elevational view of the stopper in place on a bottle, the latter being 20 shown in broken lines.

Figure 2 is a side elevational view of the same after it has been released.

Figure 3 is a plan view of the stopper in the position shown in Figure 2.

25 Figure 4 is a central cross-sectional view of the complete stopper, in side elevation, in closed position.

Figure 5 is a front elevational view of the complete stopper in released position.

30 Referring now in detail to the drawings, the numeral 1 represents a milk bottle having the neck 2 and the enlarged mouth 3. The stopper comprises a flat disk 4 having a plurality of spaced apart, resilient tongues 35 5 extending downward therefrom and curved in conformity with the rim of the mouth 5. Said tongues are of a substantially V shape and the lower ends thereof are curved so as to provide a support for a 40 ring 7 of metal wire, as shown at 6. The said ring is open and the two ends of the wire forming the same extend outward and end in eyelets 9, the portions 8 of said wire inclining slightly toward each other as they 45 so extend from the ring.

A handle member 11 is also composed of metal wire, and is pivotally supported in the eyelets 9; the portions 10 thereof being mutually parallel.

50 A coiled spring 13 is secured to the underside of the disk 4 at one end as indicated at 14, the other end thereof being attached to a cap 12 of rubber, stiff paper, or the like. A wire 15 is secured about the neck 2 of

the bottle, and an eyelet 17 is formed therein 55 in which is pivotally engaged a short link 16 which is at its other end attached to the ring 7. This prevents the stopper from falling from the bottle, or from becoming separated from the bottle.

60 In operation, assuming that the stopper as shown in Figure 3 is to be applied to the mouth and neck of a bottle, the same is placed upon the mouth and the handle member 11 is turned downward. Since the portions 10 of said handle are mutually parallel, and the portions 8 of the extensions of the ring 7 are mutually inclined toward each other, upon depression of the handle 11 the portions 8 are forced toward each other, thus 65 70 clamping the ring 7 tightly about the neck. Thereby also the spring 13 is depressed and the cap 12 is forced downward inside the neck of the bottle, thus effecting a leak-proof stopper. The pressure of the spring upon 75 the cap after the whole is in place prevents the cap from becoming loose. When the handle 11 is raised in order to open the stopper, the force of the spring 13 caused the complete device to spring upward, including the cap 12, and the same springs 80 over the side of the bottle, and is finally retained by the link 16.

85 Thus it is apparent that I have provided a milk bottle stopper which is simple in construction and operation and practical in use.

I claim:

90 A device of the class described comprising a disk or the like, resilient members extending downwardly from said disk and shaped in conformity with the mouth of the bottle, the lower extremities of said members being curved upward, a resilient wire supported in said curved extremities and adapted to 95 fit snugly about the mouth of the bottle, the ends of said wire extending outward from said bottle and being inclined mutually toward each other, eyelets on the extremities of said ends, a handle pivotally mounted in 100 said eyelets, portions of said handle extending from said eyelets and being mutually parallel and adapted to contact with said 105 ends of said wire so as to force said ends toward each other, and a cap resiliently supported on the underside of said disk.

In witness whereof I affix my signature.

THEODORE KOZLOSKY.
